POCKET TYPEWRITER WITH ROTARY AND
TRANSLATORY WORK SUPPORT

Maurice Julliard, Paris, France

Application July 24, 1948, Serial No. 40,503
In France April 28, 1948

6 Claims. (Cl. 197—2)

1

The object of the present invention is a typewriter so designed as to have small dimensions, to such a degree that it can be contained in an average size pocket and can be utilized without any support, being simply held in the hand.

To this effect, in accordance with a first characteristic of the invention, the usual typing roller, which is heavy and cumbersome and which causes an unbalance of the machine owing to the excess weight of the rear part, is omitted; the types, instead of being recorded along parallel lines, as usual, are recorded along a curved line winding around a center and approaching gradually closer to this center.

To cause this curvilinear typing, the sheet of paper, preferably circular, is associated with a supporting plate which is itself preferably circular and driven in a rotational movement around its center and, simultaneously in a rectilinear translational motion, each step by step displacement being caused by a stroke or other equivalent action on a key with a view to the recording of a character or to the obtention of a spacing.

This result may be obtained by causing a toothed pinion capable of rotating around its axis and of advancing by one tooth each time a key is acted upon, to gear with a series of holes suitably spaced on the rear face of the supporting plate and located along a curve corresponding to that along which the letters must be recorded, said plate being guided so as to be able to move according to a rectilinear motion of translation while pivoting about its center.

To this effect, the supporting plate may be mounted rotationally around an axis carried by a frame which can itself slide freely according to a rectilinear motion of translation.

Other features of the invention will be apparent from the following description of a particular type of embodiment with reference to the appended drawings wherein:

Figure 1 is a view in plan.

Figure 2 is a view from underneath.

Figure 3 is a view in longitudinal section, along line III—III of the previous figures.

Figures 4 and 5 are side views showing respectively the machine in its operating condition and opened for changing the paper.

Figure 6 shows a detail.

Figure 7 shows the paper used.

Figure 8 shows the same paper folded concertina-wise, as it is placed in the machine.

Figure 9 shows a variant.

The machine shown comprises a casing 1 and keys 2 capable of controlling each a type carry-

2

ing bar 3 through a flexible rod device 4 such, for instance, as the one which is an object of my copending patent application Serial No. 40,501, filed July 24, 1948.

5 The characters are recorded on the sheet of paper 5 by means of the inked ribbon 6 whose particular features will be indicated later; every time a key is acted upon, a forward displacement of the transverse rod 7 is caused, which rotates 10 the lever 8 actuating the bar 9 carrying a pawl 10 and rotates the toothed wheel 11 by one tooth; this toothed wheel 11 is rotationally associated with a shaft 12 whereon is keyed the conical pinion 13 engaging the conical pinion 14 keyed on the shaft 15 at the other end of which is keyed 15 the pin carrying pinion 16.

The pin carrying pinion 16 may have its pins engaged in the holes 17 arranged in the supporting plate 18 along a curve which winds around 20 the center of said plate, approaching constantly closer to said center; this center is materialized by a part 19 with which the supporting plate is associated for motions of rotation and translation, comprising a square head 20 which drives 25 rotationally the sheets of paper 21 and a circular base 22 rotationally mounted in the transverse plate 23, extended on both sides by longitudinal arms 24 which guide its longitudinal sliding.

The sheets of paper 21, which are circular, are provided, at their center, with a quadrangular perforation 25 engaged on the square head 20; they are pushed upwards by the four flat springs 26, with the interposition of a paste-board plate 26a which serves them as a base, and held at the upper part by dome 27 covering the square head 20 and pushed towards the latter by the flat spring 28.

Between two superposed sheets and below the upper sheet 5, the striker plate 29 is inserted, carried by the transverse rod 29a which also 30 carries a knife 30 whose function will be explained presently.

The sheets of paper 21 preferably consist of discs 21b, 21c, 21d, joined together by gluing 31; a common portion of paper may also be left, advantageously, common to the various discs 21b, 21c, 21d, and a line of perforations 31 may be provided which facilitates their separation, said separation being effected automatically by the knife 30 during the rotation of the supporting plate 18, and of the sheets of paper 21 which rotate at the same time. The discs 21b, 21c, 21d . . . connected together as has just been described, are folded concertina-wise and constitute a supply of paper whose quadrangular 45 perforations 25 are engaged on the square head 50

3

20 after the dome 27 has been lifted against the opposing action of the flat spring 28 and after the casing has been opened as shown in Figure 5.

To withdraw the sheet of paper which has just been typewritten and which has been separated from the adjacent sheet by the knife 30, it is only necessary to lift the dome 27 and to exert a pull on the edge of the sheet raised by the striker plate 29; a cam device or the like may be provided to cause the raising of said dome 27.

The inked ribbon 6 is an endless ribbon passing underneath the guide 32 of the type carrying bars 3, held by parts 33; it passes over the rollers 34 provided at each of the four corners of the machine; it is driven in parallel displacement by the knurled pinion 35, itself associated in rotation with the conical pinion 36 engaged with another conical pinion 36a itself keyed on an extension 37 of the shaft 15. Said ribbon is pressed against the knurled pinion 35 by a roller 38 carried by a part 39 attached at the end of a flat spring 40; another flat spring 41 carries a part 42 provided with a roller which ensures the tension of the inked ribbon 6.

In the variant shown in Figure 9, the casing 43 comprises a recess 44 corresponding to each one of the keys and the latter consist of fingers 45 arranged in each of the recesses and not extending above the upper surface of the casing 43; these fingers 45 are extensions of the flexible rods 4 for the control of the type carrying bars; with this device, instead of striking the key it is pulled forward with the finger. It will be realized that such an arrangement offers the double advantage of eliminating any projecting member, which is awkward for a machine designed to be carried in a pocket, and of facilitating for the user, the finding of the keys by the position of the corresponding recesses which he can feel with the fingers instead of being obliged to look at them. It may be used with a control such as that shown in the previous figures.

It must be understood that the type of embodiment of the invention described above with reference to the appended drawing has been given by way of indicative and non-limitative example and that numerous variants may be designed within the scope of the present invention.

What I claim is:

1. A pocket typewriter comprising keys corresponding to the various letters, pivoted type carrying levers, linking strips between the keys and the pivoted levers to set these levers in motion by the action of the keys, a supporting plate endowed both with a rotational motion and a rectilinear translational motion for receiving circular sheets of paper on which the typing is to be effected along a curved line around the center of rotation, and means for causing, by the action of the keys, a step by step rotational and translational displacement of the plate and of the sheets of paper it carries at each character recording or spacing operation.

2. A pocket typewriter comprising keys corresponding to the various letters, pivoted type carrying levers, linking strips between the keys and the pivoted levers to set these levers in motion under the action of the keys, a centrally pivoted supporting plate for carrying circular sheets of paper on which the typing is to be effected along a curved line around the center, a series of suitably spaced holes provided on the rear face of the supporting plate along a curve corresponding to that along which the types are to be recorded, a

4

rotatory pinion provided with pins engaging with the holes of the supporting plate, means for rotating said pinion by one tooth at each stroke on a key, and lateral guides for said supporting plate so that the latter may be displaced according to a translational motion at the same time that it pivots around its pivot center.

3. A pocket typewriter comprising keys corresponding to the various letters, pivoted type carrying levers, linking strips between the keys and the pivoted levers to set these levers in motion under the action of the keys, a supporting plate endowed both with a rotational motion and a rectilinear translational motion for supporting circular sheets of paper on which the typing takes place along a curved line around the center of rotation, means for causing, by the action of the keys, a step by step displacement of the plate and of the sheets of paper it carries at each recording or spacing operation, an endless inking ribbon, and means including a rotary knurled pinion for advancing said ribbon under the action of the keys.

4. A pocket typewriter comprising keys corresponding to the various letters, pivoted type carrying levers, linking strips between the keys and the pivoted levers to set these levers in motion under the action of the keys, a supporting plate endowed both with a rotational motion and a rectilinear translational motion for carrying circular sheets of paper whereon the typing takes place along a curved line about the center of rotation, means for causing, by the action of the keys, a step by step displacement of the plate and of the sheets of paper it carries at each recording or spacing operation, and a striker plate engaged under the upper paper sheet to separate this sheet from the other sheets.

5. A typewriter comprising a base plate provided with recesses whose number corresponds to that of the keys, keys corresponding to the various letters and consisting of fingers housed inside said recesses, pivoted type carrying levers, linking strips rigidly attached to the keys and connected to the pivoted levers to set these levers in motion under the action of said keys, a supporting plate endowed both with a rotational motion and a rectilinear translational motion for supporting circular sheets of paper whereon the typing takes place along a curved line around the center of rotation and means for causing, by the action of the keys, a step by step displacement of the plate and of the sheets of paper it carries at each recording or spacing operation.

6. In a typewriter, a rotatory and transversely movable support for carrying a stack of circular paper sheets whereon typing is to be effected along a curved line winding around the center of rotation and approaching uniformly closer thereto, in combination with a knife engageable under the top paper sheet for producing automatically the separation of this sheet in response to the rotation of the support.

MAURICE JULLIARD.
